FLOOR STRUCTURE OF CONCRETE SLATS

Edward J. Hatten, Stacyville, Iowa 50476

Filed May 7, 1970, Ser. No. 22,876

Term of patent 14 years

Int. Cl. D25—01

U.S. Cl. D13—1

FIG. 1 is a perspective view of a floor structure of concrete slats showing my new design,

FIG. 2 is an end view thereof from the left side of FIG. 1,

FIG. 3 is an end view thereof from the right side of FIG. 1,

FIG. 4 is a top view thereof,

FIG. 5 is a bottom view thereof,

FIGS. 6 and 7 are respective opposite perspective views of the slat making up the floor structure in FIG. 1, and FIG. 8 is a side view of said slat.

I claim:

The ornamental design for a floor structure of concrete slats, as shown and described.
